UNITED STATES PATENT OFFICE

WILLIAM L. WHITTINGTON, OF JEFFERSON CITY, MISSOURI, ASSIGNOR OF ONE-HALF
TO NATHAN C. WALDRAM, OF JEFFERSON, MISSOURI

RAILWAY-SWITCH MECHANISM

Application filed September 27, 1929. Serial No. 395,688.

This invention relates to improvements in railway switch mechanism, and more particularly to improved mounting means for switch strands and other apparatus having operative connection with railway switch or signal devices.

An object of the present invention is to provide improved means for adjustably mounting railway switch and signal actuation mechanism.

A further object of the invention is to provide means in connection with the mountings of switch and signal stands and the like, whereby to enable a ready adjustment of the operative connection between such mechanism and the movable switch members.

A still further object is to provide an improved adjusting and mounting mechanism for use in connection with switch and signal apparatus, which permits practically a micrometric adjusting between the actuating and actuated portions of a switch assembly, and which may be constructed of standard, stock materials, and which may be adjusted originally, and thereafter as may be necessary, without involving any particular degree of skill.

A still further object of the invention is to provide a mounting for switch and signal stands, which may be permanently secured to suitable headblocks or switch ties and which embodies means whereby the device may be adjusted distantly and angularly with respect to the headblocks and movable switch members without disturbing its permanent mounting.

Further objects and advantages of the invention will appear from the following detailed description of parts, and from the accompanying drawings, in which:

Fig. 1 is a top or plan view of a switch stand, together with an adjustable mounting therefor, constructed in accordance with the present invention, and Fig. 2 is a side elevation of the device appearing in Fig. 1.

As will be readily understood by those familiar with the art to which the present invention pertains, the prevailing practice in installing and adjusting a switch stand consists, for example, in employing a pair of headblocks or ties, extended parallel to each other to

points conveniently distant from the switch point to be thrown. The prevailing practice consists in mounting a switch stand by a suitable mounting plate, spiked by the usual track spikes, to one or more of the headblocks or ties, the stand being disposed in bridging relation between a pair of such ties. Obviously, it is extremely difficult, at the first setting, so to locate the stand angularly and distantly with respect to the headblocks and switch points that, with the switch lever at one limit of its movement, the movable switch points fall exactly at their proper limit of movement. Due to vibration, changes in temperature, disturbance in ballasting, wear in the switch actuating assembly, and other numerous causes, the adjustment of a switch stand is frequently disturbed, relative to the switch points. It has heretofore been necessary, in such a case, to draw the spikes securing the stand to the headblocks, to plug the spike holes, and to reset the stand at a different position of the headblocks. Obviously, considerable skill is required successively to locate a switch stand and like devices under such conditions, since the proper setting of the mechanism involves very often, not only a proper distance relation between the mounting plates, but also a proper angular setting for adjustment. It is to the fulfillment of these requirements, as well as the objects enumerated above, that the present invention is directed.

The present disclosure is directed particularly and in detail to a single illustrative embodiment, but it will be readily understood that the parts and certain features of their arrangement may be varied substantially without departing from the intended scope of the invention.

Referring now by numerals to the drawings, the headblocks or ties, of which a pair are preferably employed, are indicated at 3. These blocks are, by preference, extended in parallel relation laterally from the rails opposite the switch points to be actuated. Secured to each of the headblocks, by preference near the track end of the assembly, are a pair of anchor plates 4 disposed by preference opposite each other and each secured to one of the headblocks as by a plurality of

track spikes 5. Plates 4 are each characterized by an upstanding flange 6.

- Movably mounted and preferably originally spaced from the plates 4, are a pair 5 of angle plates 7, substantially longer, by preference, than the plates 4, and each provided, as will best appear in Fig. 1, with slotted openings 8, at least a pair of which are provided in each of the plates 7 for adjustment purposes, as will hereinafter appear. The plates 7 are further provided with upstanding flanges 9, presented oppositely to the flanges 6. Adjustable securing of the plates 7 is effected, in the present example, 10 by means of bolts of a length sufficient to extend upwardly through and beyond the headblocks and through the slotted openings 8, these bolts being indicated at 10 and provided on their exposed ends with nuts 11 15 and suitable washers overlying slots 8. Obviously, the slots 8 may be disposed centrally or otherwise in the plates 7; it is preferred, however, to construct the plates substantially uniformly, as shown, whereby to avoid the necessity of providing right- and left-handed 20 mounting members.

Mounted on each of the plates 7 is a switch lock assembly 12, which may be of usual construction, and each of which may be secured 25 to its mounting plate as by bolts 13, the heads of which are, by preference, countersunk in the under surface of plates 7, whereby the nuts thereon may be actuated from the exposed side of the mounting plates. The lock 30 assemblies 12 serve, as is clearly understood in the art, as retaining or locking means for a switch lever 14. The switch stand 15 may be of any desired or usual construction and includes a vertical, rotatable member or mast 35 16. connected as by a crank or arm 17 to a switch arm 18, to effect a reciprocating movement of the latter element, upon a partial rotation, or "throw" of the lever 14, all as well understood.

The mounting of the switch stand is effected by means of a foot portion 19, there being one of these at each side of the stand, and secured as by a plurality of bolts 20 to the plates 7, the bolts 20 being, by preference, 40 countersunk after the manner of the bolts 13. As will best appear in Fig. 2, the openings for the bolts 20 are made substantially larger than the bolts, in order to permit of relative angular adjustment between each 45 of the portions 19 and its associated plate 7. Secured to each of the feet at opposite sides of the stand, is a bolt 21, engaging one of the feet 19.

Means for moving the switch stand and 50 certain of its mounting members, distantly, along the headblocks, is found in the vertical or upstanding flanges 6 and 9, each of which is apertured, by preference, centrally, as at 55 22 and 23. Extending between and beyond the paired apertures, is a jack screw 24,

preferably a bolt of substantial size, threaded over its entire length, this bolt being so related to the apertures 22 and 23 as to move freely therethrough, except as the jack screw is positioned by means of a plurality of nuts thereon, such as 25, 26, 27 and 28, the arrangement preferably being the same between each pair of the plates 4 and 7. Obvious variations of this arrangement may at once suggest themselves, for example, internally threading the openings 22 and 23, and employing a head portion on the bolt 24, for adjusting purposes. The advantages and manner of use of the described adjustment means, will be at once apparent to those skilled in the art, but may be here briefly reviewed for the sake of completeness of description.

To effect an adjustment or setting of the switch operating mechanism, the nuts 25, 26, 27 and 28 may be backed away from the flanges 6 and 9, the nuts 11, as well as the nuts on bolts 20, are loosened, after which the stand becomes distantly and angularly movable relative to the headblocks and switch points. With the operating arm 18 connected to a switch point in one extreme position and with the operating lever 14 suitably positioned, the switch stand, being freely movable, will tend to assume substantially its correct operating position. An exact setting may then be effected, for example, by loosening a pair of the nuts on each headblock, such as 25 and 26, and correspondingly taking up nuts 27 and 28, or vice versa, according to the direction of adjustment necessary to effect a proper distance placement of the stand.

In case any angular adjustment is necessary it will be obvious that, the nuts on bolts 20, having previously been loosened, either of the plates 7 may be advanced or retracted relative to the other in a manner to move the stand about its middle point or axis. For effecting micrometric angular adjustment, one pair of the flanges 6 and 9 may be brought closer together by the related jack screw 24, while the opposite pair of flanges are spread farther apart by an opposite adjustment of the jack screw therein. In certain cases, due to differences in dimensions of the headblocks, or irregularities in ballasting, it may be necessary to plumb, or vertically align the stand. This may obviously be effected by the use of auxiliary plates or shims (not shown), located between the headblocks and plates 7. Upon completion of the angular and distance adjustments, the nuts on bolts 20 are taken up, as are the nuts 11, 25, 26, 27 and 28. Obviously, this adjustment may be effected as often as necessary, and by anyone, without particular skill.

A number of advantages attained by the use of the described mechanism will be ap-

parent to those skilled in the art. By preference, four separate mounting plates are employed, as it is usually necessary in adjusting switch points to fit properly against both rails, that the base plates be moved to a certain extent in opposite directions. Such an adjustment is not possible with a one piece base-plate, nor can it be readily effected by an ordinary set screw, such as is used in other adjusting devices.

10 A further structural advantage may be noted, in that, with a connection properly effected between the pair of base plates by the use of the screw 24 when the adjustment is made, the strength of the device is practically equal to that of a solid base plate.

15 Further advantages may be noted in that labor cost is substantially decreased due to the simplicity and ease of adjustment, only a few minutes time being required to make any desired adjustment between the stand and switch points. The nuts employed throughout the assembly are preferably of such size that the only tool required in making an adjustment is an ordinary track wrench.

20 25 Further advantages may be noted in that it is never necessary, as with the prevailing practice, to draw the reset spikes, such a practice resulting in a weakened condition of the ties. This undesirable feature is completely eliminated by the present construction, which further insures a smooth-working assembly at all times.

30 35 Since the parts incident to the use of the present improvements consist entirely of stock materials, any additional cost incident to installing the present adjusting mechanism, becomes negligible in proportion to the advantages attained.

40 I claim as my invention:

45 1. In combination with a switch actuating assembly, a support for the assembly, means for adjusting the position of the assembly on the support, said means including a mounting member between the assembly and support, and screw-threaded means for moving the mounting member to adjusted positions along the support.

50 55 2. In combination with a switch actuating assembly and a support therefor, means for supporting the assembly in adjusted positions along the support, said means including a holding element extending from the support, a mounting member disposed between the assembly and support, and secured to said assembly, the mounting member having a passage for said holding element and arranged to permit adjusting movement of said element, across said passage.

60 65 3. In combination with a switch actuating assembly and a support therefor adjustable mounting means including a slotted mounting base, carried by said support and disposed between said assembly and support, holding means secured to said support and extending

through the slots in said mounting member, and means for securing said actuating mechanism to the mounting member.

4. In combination with a switch actuating assembly and a support therefor, adjustable mounting means including an anchor member secured to said support, a mounting member carried by said support and constituting a carrier for the actuating assembly, screw threaded means for varying the distance relation between said anchor member and mounting member, and means for securing the actuating assembly to said mounting member.

5. In combination with a switch actuating assembly and a support therefor, adjustable mounting means including a pair of mounting members constituting a base for said actuating assembly, and carried by said support, and means for effecting independent adjustment of said mounting members with respect to said support.

6. In combination with a switch actuating assembly, adjusting and mounting means therefor including spaced pairs of mounting members, certain of said members forming supports for the actuating assembly, and screw threaded means for independently varying the distance adjustment relation between said pairs of mounting members.

7. In combination with switch actuating mechanism and a support, adjustable mounting means including a pair of mounting members serving to carry said actuating mechanism, said mounting members being carried by, and independently movable relative to said support, and separate screw-threaded means for moving said mounting members to adjusted positions with respect to the support.

8. In combination with switch actuating mechanism, including a pair of supporting members, adjustable mounting means including a slotted mounting member carried by each of said supports, holding means secured to said supports and extending through the slots in said mounting members, screw threaded means for effecting a distance adjustment of each of said mounting members with respect to the supports, and means for securing said mechanism to said mounting members.

9. In combination with switch actuating mechanism, and a pair of supports, adjustable mounting means including a mounting member associated with each support, means for effecting independent distance adjustment of said mounting members with respect to said supports, and means for angularly adjusting said actuating mechanism with respect to each of said mounting members.

10. In combination with switch actuating mechanism, including a pair of spaced supports therefor; an anchor member on each of said supports, a mounting plate slidably

disposed on each of said supports and normally spaced from said anchor members, and screw-threaded adjustment means for independently varying the distance relation between each of said mounting plates and its associated anchor.

11. In combination with a switch stand, including a pair of spaced headblocks, adjustable mounting means for said stand, including a slotted plate slidably disposed on each of said headblocks, bolts extending from the blocks through the slots in said plates, screw-threaded means for independently adjusting the position of said plates along said headblocks, and anchoring means associated with the screw-threaded means.

12. In combination with a switch stand and spaced headblocks for supporting said stand, adjusting and mounting means adapted for readily altering the adjustment of said stand relative to the switch points, said means including a pair of slotted mounting plates, one disposed on each of said headblocks, a pair of anchor plates, one thereof being disposed on each of the headblocks, and normally in spaced relation from said mounting plates, each of said plates having an upstanding apertured flange thereon, a jack-screw extending between the paired flanges and being provided with adjusting nuts adjacent each of said flanges, mounting feet for said stand having apertures therein, and bolts extending from said mounting plates in spaced relation through said apertures, bolts extending from the headblocks and through the slots in said mounting plates, holding means for securing said feet to said mounting plates, and means formed by said apertured feet, jackscrews and associated nuts, whereby each side of the switch stand may be independently adjusted, angularly and distantly, with respect to the headblocks and switch points.
